Primary Examiner — Lauren R Calve(74) *Attorney, Agent, or Firm* — Scully Scott Murphy and Presser(57) **CLAIM**

The ornamental design for a garment hanger for underwear, as shown and described.

DESCRIPTION

FIG. 1 is a perspective view of a garment hanger for underwear showing my new design;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

The broken lines depict portions of the garment hanger for underwear that form no part of the claimed design.
